UNITED STATES PATENT OFFICE.

CHRISTOPHER A. GOETZE, OF MINNEAPOLIS, MINNESOTA.

DESIGN FOR A TIRE-TREAD.

51,230.

Specification for Design. **Patented Sept. 4, 1917.**

Application filed October 14, 1916. Serial No. 125,742. Term of patent 7 years.

To all whom it may concern:

Be it known that I, CHRISTOPHER A. GOETZE, a citizen of the United States, residing at Minneapolis, in the county of Hennepin and State of Minnesota, have invented a new, original, and ornamental Design for Tire-Treads, of which the following is a specification, reference being had to the accompanying drawings, forming part thereof.

Figure 1 is a perspective view of a portion of a tire employing my tread. Fig. 2 is a developed view of the tread.

I claim:

The ornamental design for a tire tread, as shown.

CHRISTOPHER A. GOETZE.

Witnesses:

H. A. BOWMAN,
ALEX. LAGAARD.
